MICHAEL J. STEIN, OF NEW YORK, N. Y.

Letters Patent No. 88,227, dated March 23, 1869.

IMPROVED LAST-HOLDER FOR THE MANUFACTURE OF BOOTS AND SHOES.

The Schedule referred to in these Letters Patent and making part of the same.

To all whom it may concern:

Be it known that I, MICHAEL J. STEIN, of the city, county, and State of New York, have invented a new and useful Improvement in Last-Holders for the Manufacture of Boots and Shoes, of which the following is a full, clear, and exact description, reference being had to the accompanying drawing, forming part of this specification, and in which—

Figure 1 represents a side elevation of a last-holder, or jack, constructed in accordance with my improvement, and showing a last arranged thereon;

Figure 2, a transverse section of said holder, through the line $z z$ in fig. 1; and

Figure 3, an inverted plan of the adjustable plate, or frame-portion of the holder, and its attachments, with the base, or carrying-plate removed.

Similar letters of reference indicate corresponding parts.

This, my invention, is more particularly designed to be applied to a loose jack, or last-holder, capable of being slid about, in various directions, on a bed, or table, for the purpose of adjusting the work to the action of the needle, as in machines for sewing the upper to the sole in turned boots and shoes, or upper and welt to an inner sole, in welted work.

The invention consists—

First, in a novel construction of the jack, whereby the last is carried by a plate, or frame, arranged above the base, or carrying-plate of the holder, and adjustable, in a vibratory manner, thereon, so that, while the jack, or last-holder, generally, may be slid as required over the table on which it rests and moves, the adjustable last-supporting plate, or frame, with its attachments for securing the last, may be separately adjusted, or rocked, to give a reverse vertical adjustment of the last at its toe and heel, and intermediate portions, for the purpose of facilitating stitching, or working, on crooked lasts.

Secondly, the invention consists in a combination of a dog, or dogs, and rack, or their equivalents, with the adjustable last-holding plate, or frame, and base-plate of the jack, for locking, or stopping the adjustable plate, or frame, at different elevations, or angles.

Referring to the accompanying drawing—

A is the base, or carrying-plate of the jack, designed to rest on the surface of the table, so that it may be slid thereon in any direction required.

B are standards, or uprights, erected, one on either side of the base-plate A, and serving to carry, by trunnions $a a$, and suitable side connections, or extensions $b b$, a last-carrying plate, or frame C, arranged above the base-plate A, and adjustable in a vibratory manner, or in reverse vertical directions, at its opposite ends, from the trunnions $a a$ as centres of motion.

D represent the last, which has a hole made in the upper part of it, to fit a perpendicular stud, c .

This pin, or stud, is fitted to and secured in a socket, d , by a set-screw, e , which socket is carried by a base,

or plate, e^* , adjustable by a slotted attachment and locking-nut, and screw, f , along ways $g g$, on the upper surface of the plate C, to admit of the shifting and securing of the pin c , at varied distances from the end of said plate, to suit large and small lasts.

Toward the opposite end of the plate C, is a base-block, h , adjustable along the ways $g g$, for the purpose of sliding it toward or from the pin c .

A crutch, i , of a suitable shape to bear up against the inverted instep of the last, is fitted with a cylindrical stem, k , arranged to slide up and down in a socket, l , carried by the base-block h ; and a projection, m , from the side of this stem, is made to bear on the periphery of a cam, n , fast to a short arbor, mounted in a projection from the base-block, and provided with a handle, o , so that the operator, by turning the arbor, causes the cam n to lift the crutch, and thus force it up against the instep of the last, and, as the last is fitted on to the pin c , the same, by the force applied to its toe-end, becomes firmly secured to the plate, or frame C.

The base-block, which carries the crutch, may be secured at its required distance from the pin c by any suitable means, as, for instance, by a second cam, arranged on the arbor to which the handle o is attached, and made to act on the upper end of a spring-clip, to force it down into contact with the upper surface of the plate C, the two cams being so arranged, in relation to each other, as that, by moving the handle o , the base-block is first secured in position before the crutch is forced up against the instep of the last.

The swinging, or adjustable plate, or frame, C, hung, as described, by the trunnions $a a$, may be provided, at or near its back end, with an adjustable stop, or pin, E, arranged to screw into or through the base, or plate e^* , to limit the downward adjustment of the heel-portion of the last, and give said frame C a fixed character, as it were.

To facilitate working on a crooked last, I tip, or tilt the plate, or frame C, by rocking it on or by means of its trunnions $a a$, for the purpose of elevating or depressing the toe or heel, or intermediate portions of the last, and, when so adjusted, cause the frame C to be locked in the varied angular position thus given it. This is accomplished by means of dogs, $r r$, arranged to project from, or attached to slotted plates F F, made capable of sliding in a transverse direction to the plate C, with which they are connected, said dogs being so set, or arranged, as, when the plate, or frame C is rocked, to enter alternately between teeth, $s s$, of a rack, G, attached to the base-plate A, and alternately to bear against the outer faces, or edges of said teeth. This duplication of holding-dogs, and set of them relatively to the rack, provides for a rapid, yet close, or nice adjustment of the last-holding frame C, by either one dog being always at liberty, or nearly so, except when purposely restrained, to enter between the teeth of the rack, to lock the frame C at the angular set given

by rocking it, while the other dog, during such motion to said frame, rests on, or is travelling over the outside edge of a tooth, for gear with the rack as the first-named dog leaves it.

Springs, H H, arranged to act upon the slides F F, serve to throw and keep the dogs *r r* alternately in locking-connection with the rack, and said dogs are released from gear therewith, when it is required to swing or angularly adjust the last-holding frame and last, by pressing inward handles, or levers, I I, which are connected with the slides F F, by means of pins *u u*, made to fit, or enter slots *v v* in both, or opposite ends of said slides, so that, by pressing inward either lever H H, or both of them, the adjustable frame, or plate C is released from lock, and by releasing pressure from said handles, the lock re-established through the agency of either spring H H.

What is here claimed, and desired to be secured by Letters Patent, is—

1. The combination, with the movable base-plate A, of the swinging last-holding plate, or frame C, provided with adjustable toe and heel-supports *i e*, for operation substantially as described.

2. The combination of a locking-dog, or dogs, and rack, with the adjustable, or swinging last-holding plate, or frame, and base-plate, or portion of the jack, for locking, or stopping the last-holding plate at different angles, or elevations, essentially as described.

3. The combination, with the base-plate A and adjustable, or rocking last-holding plate C, of the rack G, the slotted slides F F, the springs H H, the levers I I, and the dogs *r r*, carried by said slides, and set, or arranged relatively to the teeth of the rack, for operation substantially as specified.

MICHAEL J. STEIN.
